CLAY PIN DRYING AND CUTTING
MACHINE

William W. Irwin, East Liverpool, Ohio, assignor,
by mesne assignments, to The Potters Supply
Company, East Liverpool, Ohio, a corporation
of Ohio

Application December 2, 1933, Serial No. 700,728

10 Claims. (Cl. 25—105)

The invention relates to a machine similar to that disclosed by U. S. Patent 1,315,507, patented September 9, 1919 by De Witt D. Irwin. This machine effected partial drying of strips of clay, 5 transversely cut the partially dried strips into pins, and then completed the drying operation so that the pins were in readiness for firing to be used as "saggar pins" or the like in supporting articles of pottery while baking in kilns. The 10 machine in question cut both ends of the pins at right angles to their lengths, but it has been found that if one end of the pin be cut obliquely, a much sharper corner will exist for contact with the ware, so that the inevitable blemishes caused by 15 contact of the pins with the ware will be reduced to the minimum. It is therefore one object of the present invention to provide an improved cutting means which will cut the pins with the desired bevel, at least at one end.

20 A further object is to provide a new and improved machine which will cut the pins into the most preferred shape, that is, with a bevel at one end and no bevel at the other end, allowing the latter to be more snugly received in the usual pin 25 socket, than if it also were beveled.

The strips of clay from which the pins are cut, are extruded onto boards which are placed upon driven endless chains and carried thereby through the drying tunnel of the machine, and during 30 their travel, the pins are cut, and a further object of the invention is to provide unique mounting means for the cutting disks, and spring means normally urging said disks toward said boards so that the disks may float to any extent which may 35 be required, due to uneven thicknesses of the boards, warping, etc.

A still further object is the provision of a construction which is simple and inexpensive, yet efficient, reliable and durable.

40 With the foregoing in view, the invention resides in the novel subject matter hereinafter described and claimed, description being accomplished by reference to the accompanying drawings.

45 Fig. 1 is a vertical transverse sectional view through a drying tunnel and the pin board conveying means, showing the improved cutting mechanism in elevation, this view being cut on line 1—1 of Fig. 2.

50 Fig. 2 is a fragmentary, vertical longitudinal sectional view on line 2—2 of Fig. 1.

Fig. 3 is an enlarged sectional view partly in elevation, similar to a portion of Fig. 2.

55 Fig. 4 is a fragmentary top plan view, partly in horizontal section on line 4—4 of Fig. 3, showing

a number of the cutting disks and their mounting means.

Fig. 5 is an end elevation looking in the direction of the arrow A of Fig. 3.

Fig. 6 is a view similar to Fig. 3 but showing a 60 modification.

Figs. 7, 8 and 9 are respectively a top plan view, a side elevation and an end view of one of the pins cut by the machine.

A drying tunnel T is shown having a heat insulating lining L, said tunnel being supported by rigid side frames F. Within the tunnel are parallel rails R supporting the upper reaches of endless driven conveyor chains C, said chains having supports S for the pin boards B. These boards 65 support the transversely triangular clay strips s, carry them through the drying tunnel T to dry them sufficiently for cutting, then carry said strips under the improved cutting mechanism M, and then convey the cut pins on through the tunnel 70 to complete drying thereof in readiness for firing.

All of the cutting mechanism is preferably mounted upon a single shaft 10 which extends transversely through the tunnel T and may have 75 its ends secured non-rotatably at 11 upon the side frames F. This cutting mechanism, in the present disclosure, consists of a plurality of units 12 which are duplicates of each other, and two more units 12^a and 12^b respectively, which with 80 certain exceptions, are duplicates of said units 12. Each of the units 12 is provided with a vertical cutting disk 13 and with an inclined cutting disk 14, but unit 12^a is provided only with an inclined disk 14^a, and unit 12^b is provided 85 only with a vertical cutting disk 13^b. The various disks are so arranged that those standing perpendicular to the pin supporting means, will cut one end of the pins P at right angles to the 90 lengths of said pins, whereas the inclined disks 95 will obliquely cut or bevel the other ends of the pins, producing an unusually sharp corner P' for contact with the ware, when the finally completed pins are used during kiln baking of said ware.

100 Each of the units 12, 12^a and 12^b includes a bracket 15 having a hub 16 keyed at 17 upon the shaft 10 and held in any position to which it may be slid, by a set screw 18. The hub 16, for ease of application of the shaft, is preferably 105 formed of two sections secured together by cap screws or the like 19. Integral with one section of this hub is laterally projecting lug 20 to which two vertically swingable arms 21 and 22 are pivoted at 23 and 24 respectively, the arm 21 110

carrying the disk 13 while the disk 14 is carried by the arm 22. Above these swingable arms, the bracket 15 is provided with a laterally projecting rigid arm 25 which is preferably separate from said bracket and secured to it by cap screws or the like 26. Coiled compression springs 27 are interposed between the fixed arms 25 and the arms 21 and 22, to downwardly urge these arms and the disks carried thereby, yet to allow any required floating of the disks when encountering irregularities in the boards B. Set screws 28 having locknuts 29 are preferably threaded through the arm 25 for varying the strength of the springs 27, as may be desired. Then too, stop screws 30 having lock nuts 31 are preferably carried by the arm 25 to limit the downward swinging of the arms 21 and 22 under the influence of the springs 27, said stop screws functioning primarily after the last pin board of any run has passed under the cutting mechanism M, thereby prohibiting the disks and arms from swinging out of their proper relation with other parts.

For the unit 12^a, since the vertical disk 13 is omitted, the arm 21 and the associated spring and stop screw, such as 27 and 30, are also omitted. For the unit 12^b, since no inclined disk 14 is used, the carrying arm 22 and the associated spring and stop screw are omitted.

Should it be desired to construct the mechanism M to only cut at right angles to the lengths of the strips s, the lug 20^a and arm 25^a on a bracket 15^a corresponding to the bracket 15, may be shorter, as seen in Fig. 6. To the lug 20^a, a spring-pressed arm 21^a for a vertical cutting disk 13^a, is pivoted. A similar construction could well be used if the machine were desired to cut both ends of the pins obliquely, it being then only necessary to mount the cutting disks in inclined positions upon the arms such as 21^a.

It will be seen from the foregoing that novel provision has been made for carrying out the objects of the invention, and while the details disclosed are preferably followed, it is to be understood that numerous variations may be made within the scope of the invention as claimed.

I claim:

1. A cutting machine comprising a traveling support for material to be cut, a plurality of disks for cutting material on said support, arms upon which said disks are mounted respectively, means mounting said arms for independent swinging toward and from said support, and means for urging said arms independently toward said support.

2. A cutting machine comprising a traveling support for material to be cut, a plurality of disks for cutting the material on said support, arms upon which said disks are mounted respectively, means mounting said arms for independent swinging toward and from said support, and spring means for urging said arms toward said support.

3. A cutting machine comprising a traveling support for material to be cut, a plurality of disks for cutting the material on said support, arms upon which said disks are mounted respectively, brackets to which said arms are pivoted for independent swinging toward and from said support, means for fixedly mounting said brackets, and springs acting against said arms

and reacting against said brackets for urging said arms toward said support.

4. A cutting machine comprising a traveling support for material to be cut, a shaft parallel with and transverse to the line of travel of said support, means for mounting said shaft and holding it against rotation, a plurality of brackets spaced apart along said shaft and having hubs secured upon the same, arms pivoted to said brackets to swing toward and from said support, cutting disks mounted on said arms, and spring means acting against said arms and reacting against said brackets for urging said arms toward said support. 80 85

5. In a machine for cutting clay strips to form saggar pins, a traveling support for the clay strips, and means for transversely cutting the traveling clay strips, said means including means inclined to the lengths of said strips for obliquely cutting at least one end of each pin formed by 90 95 said transverse cutting.

6. A pin cutting machine comprising a traveling support for strips to be cut into pins, spaced cutting means mounted in positions substantially perpendicular to said support for transversely cutting the traveling strips to form one end of the pins, and additional cutting means mounted in inclined positions for transversely cutting said strips to form the other ends of the pins. 100

7. A pin cutting machine comprising a traveling support for strips to be cut into pins, spaced cutting disks substantially perpendicular to said support for transversely cutting the traveling strips to form one end of the pins, additional cutting disks inclined to said support for cutting 105 the other ends of the pins, individual carrying arms for the various disks, means mounting said arms to swing toward and from said support, and spring means for urging said arms toward said support. 110 115

8. In a cutting machine, a bracket having a hub for mounting it upon a shaft, said bracket being provided with a rigid lug projecting laterally from said hub, a disk-carrying arm pivoted to said lug, and spring means acting on 120 125 said arm and reacting on said bracket for urging said arm in one direction.

9. In a cutting machine, a bracket having a hub for mounting it upon a shaft, said bracket being provided with a rigid lug projecting laterally from said hub, and also having a laterally projecting rigid arm spaced from said lug, a disk-carrying arm pivoted to said lug, and a coiled spring interposed between said fixed arm and said disk-carrying arm for urging the latter in 130 one direction. 125

10. In a cutting machine, a bracket having a hub for mounting it upon a shaft, said bracket being provided with a rigid lug projecting laterally from said hub, and also having a laterally projecting rigid arm spaced from said lug, two arms pivoted to said lug on axes substantially unidirectional with the hub axis, a cutting disk carried by one of said pivoted arms and disposed in a plane substantially perpendicular to the hub axis, a second cutting disk carried by the other of said pivoted arms and disposed in a plane inclined to the aforesaid plane, and spring means acting on said pivoted arms and reacting against said rigid arm for urging said pivoted 140 145 arms in one direction.

WILLIAM W. IRWIN.
